Primary Examiner — Shawn T Gingrich*Assistant Examiner* — Amanda Christensen(74) *Attorney, Agent, or Firm* — Kunzler Bean & Adamson, PC; Michael Bartholomew(57) **CLAIM**

The ornamental design for a wireless charger as shown and described.

DESCRIPTION

FIG. 1 is a front, right and bottom perspective view of a wireless charger, showing my design.

FIG. 2 is a rear, left and top perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is another front, left and bottom perspective view of the wireless charger in a first usable state; and,

FIG. 10 is another front, left and bottom perspective view of the wireless charger in a second usable state.

The broken lines depict portions of the wireless charger that form no part of the claimed design.
